(57) **CLAIM**

The ornamental design for a lamp shade, as shown and described.

DESCRIPTION

FIG. 1 is a perspective view of a lamp shade, showing my new design;

FIG. 2 is a side elevational view thereof, all side views being identical;

FIG. 3 is a top plan view thereof;

FIG. 4 is a bottom plan view thereof;

FIG. 5 is a cross-sectional view thereof, taken along dashed line 5-5 illustrated in FIG. 2; and,

FIG. 6 is a side elevational view showing, without limitation, a practical usage of the design illustrated in FIG. 1, the broken lines showing portions of a lamp solely for the purpose of illustrating the lamp shade mounted on the lamp.

The broken lines illustrating portions of the lamp shade and lamp form no part of the claimed design.
